INVENTOR
L. W. LEEDS.

UNITED STATES PATENT OFFICE.

LEWIS W. LEEDS, OF GERMANTOWN, PENNSYLVANIA.

APPARATUS TO PREVENT AN OVERSUPPLY OF COAL TO THE FIRE-BOXES OF HOT-AIR FURNACES.

Specification of Letters Patent No. 13,525, dated September 4, 1855.

To all whom it may concern:

Be it known that I, LEWIS W. LEEDS, of the city and county of Philadelphia and State of Pennsylvania, have invented a new 5 and useful Improvement in Apparatus for Artificially Warming or Heating Buildings, &c.; and I hereby declare that the following is a full, clear, and exact description of the same, reference being had to the accompanying drawings, forming a part of this specification.

The nature of my improvement in heaters consists in such an arrangement thereof, that the supply of coal to the furnace may be 10 regulated, by which means waste of coal from too deep a fire, and consequent obstruction of draft through the fire pot, or coal holder, from an undue quantity of coal thrown in at any time is obviated; this evil 15 is of frequent occurrence from carelessness of attendants in furnaces of the ordinary construction. In my improvement by the introduction of space between the fire pot and walls of the furnace, on two or more sides 20 thereof, of sufficient size to permit the coal to fall through when an undue quantity is thrown on the fire pot; this evil of excess of coal is avoided but an open space, that is one through which the draft may pass must, be 25 avoided, this gave rise to the second part of my improvement by closing the space at the lower part of the fire pot by a balance valve, so pivoted as to remain in a proper position except when loaded by the excess of coal 30 from the fire pot, falling thereon and causing its turning, and thus permitting the coal in excess to fall below the pot on the sifting bars of the ash pit, from whence it may be gathered; the weighted side of the valve always insures the closing of the space.

To enable others to make and use my improvement I would describe it as follows.

Figure 1 represents a vertical central section of the apparatus, in which A, A, are the walls of the chamber; B, B, cross walls separating the air chambers from the furnace; C, a division wall separating the fire chamber from the exit gas chamber D. Above this wall C, will be noticed a dotted line representing an extended partition between the 45 pipes by which the heat and smoke is carried near the top thereof and over which it passes in its descent to chamber D, from the latter it escapes into the chimney.

E, E, E, are the air pipes, between and 55 around which the heat and gases pass; F, the fire box; G, G, the side walls thereof, over which any excess of fuel falls on the valves H, H, and by their turning delivers the excess of coal on the lower grating.

Similar letters on the several figures refer to like parts.

Having described my improvement in heaters and furnaces, what I claim as my invention and desire to secure by Letters Patent is,

The arrangement in the fire chamber of the balance valves H, H, as described for the purpose of preventing an undue quantity of coal from remaining in the fire box substantially in the manner set forth.

In testimony whereof I have hereunto signed my name before two subscribing witnesses.

LEWIS W. LEEDS.
